UNITED STATES PATENT OFFICE

96,829

DESIGN FOR A CABINET FOR TARGET PRACTICE AMUSEMENT GAMES

George A. Gast, Chicago, Ill., assignor to
Raymond T. Moloney, Chicago, Ill.

Application July 15, 1935, Serial No. 57,654

Term of patent 7 years

To all whom it may concern:

Be it known, that I, George A. Gast, a citizen of the United States, residing at Chicago, in the county of Cook and State of Illinois, have invented a new, original, and ornamental Design for a Cabinet for Target Practice Amusement Games, of which the following is a specification, reference being had to the accompanying drawing, forming part thereof.

The figure is a perspective view of a cabinet for

target practice amusement games, showing my new design.

The opposite side of the upper cabinet portion has substantially the same features and appearance of the side shown.

I claim:

The ornamental design for a cabinet for target practice amusement games, as shown and described.

GEORGE A. GAST.
